UNITED STATES PATENT OFFICE.

WILLIAM H. MATTHIES, OF HACKENSACK, NEW JERSEY, ASSIGNOR TO WESTERN ELECTRIC COMPANY, INCORPORATED, OF NEW YORK, N. Y., A CORPORATION OF NEW YORK.

INDICATING SYSTEM.

1,254,254.

Specification of Letters Patent. Patented Jan. 22, 1918.

Application filed December 29, 1916. Serial No. 139,521.

To all whom it may concern:

Be it known that I, WILLIAM H. MATTHIES, a citizen of the United States, residing at Hackensack, in the county of Bergen and State of New Jersey, have invented certain new and useful Improvements in Indicating Systems, of which the following is a full, clear, concise, and exact description.

This invention relates to telephone exchange systems in which automatic switches are used to establish connections, either wholly or in part, and is more particularly related to systems in which such switches are controlled by means of a sender located at a central office.

The object of this invention is to provide an improved arrangement for testing such senders. In senders of the reverse impulse type, that is, senders which are operated in response to the movements of a switch or switches controlled by them, the arrangement has been such that after a switch has been positioned in accordance with a setting of the sender, circuit changes will take place both at the switch and at the sender such that the switch may be controlled in another of its movements. Similarly, a succeeding switch or switches may be brought under the control of the sender, whose associated controlling device moves from position to position, upon the termination of the sending of each set of impulses.

In previously proposed arrangements, a testing circuit arrangement has been provided which will actuate a sender in a manner similar to that in which it would be actuated in response to the movements of the switches normally controlled by it.

In testing systems of this type, some form of counting device is utilized which is advanced in response to the operation of the sender, and upon the completion of the sending of a set of impulses, it is returned to its normal position ready for reoperation in response to the next set of impulses. Inaccuracies have in this way been introduced into the test, since in actual operation the sender transmits sets of impulses in rapid succession in certain stages of its operation; while, when under test, it is allowed a time interval between the sending of each set of impulses to allow the counting device of the testing arrangement to restore to normal.

Thus a sender might operate correctly when tested, but fail under actual operating conditions.

It is, then, more particularly the object of this invention to provide a testing arrangement employing a counting device which does not return to normal after being set. Although this counting device has been shown in connection with a testing arrangement, the invention is not to be restricted to such an arrangement, since a counting device of this character might be used to advantage in a variety of systems.

The sender testing device as disclosed in the present description is designed to operate in connection with senders of the type, used in power driven systems of the semi-automatic type, such as disclosed in Patent No. 1,168,319.

The testing device includes broadly a key set, a series of matching lamps, a series of progress lamps, a progress-controlling sequence switch and an impulse sending sequence switch. These devices are mounted in a suitable carriage of any convenient form, the present invention being concerned only with the circuit arrangement of the testing device.

The general operation of the arrangement is as follows: The jacks associated with the test box and indicated at 50 and 51 of Fig. 2 of the drawings, are arranged to be connected by double plug-ended links 52 and 53 to jacks 54 and 55, in which terminate lines running from the contact set of a cord finder. The cord finder will automatically hunt for calling terminals in a manner similar to that in which it seeks out a cord circuit in the regular operation of a semi-automatic system. The sender keys will be depressed in accordance with any desired number, and the person making the test will depress keys in the testing device key set corresponding to the number of impulses to be sent. The matching lamps consist of two rows of lamps, the lamps in one row being lighted during the sending of each series of impulses in accordance with the number set up by the testing operator. The lamps in the second series are lighted at proper times to indicate the number of impulses actually sent in response to the setting of the regular operator's key set. Thus, if a se-

lection is properly made, this fact will be indicated by the lighting of adjacent lamps at the close of the sending of each set of impulses. The progress sequence switch 5 controls, at its contacts, circuits to cause the lighting of matching lamps associated with the various keys in a definite order, and controls also a series of progress lamps which indicate the stage of operation and 10 inform the operator which series of impulses is being sent at any time.

A feature of the present invention is the control of indicating signals by means of a counting device which moves through a desired number of positions and then causes 15 the display of a signal indicative of the number of positions through which the counting device was moved, regardless of which position said counting device was in 20 when started.

An additional feature is the use of a set of locking relays, certain ones of which are energized in accordance with the position of the counting device at the beginning of 25 its operation. These relays also control a starting circuit which cannot be completed unless the proper combination of relays has been actuated, this circuit thus acting as a check on the operation of the relays.

30 A further feature of the invention is the use of a differentially wound relay to govern the advance of a controlling switch to prevent undesired advance of such switch in case other apparatus is not in a desired condition.

35 It is thought that the invention will be best understood from the following detailed description, reference being had to the accompanying drawings.

40 In the drawings, Figure 1 shows a calling and a called substation, together with an automatic switch, whose circuits are partially shown, and additional switches which are schematically indicated. In Fig. 2 are 45 shown the circuits of a cord finder used to associate an operator's sender and key set with a desired cord. Figs. 3, 4 and 5 disclose operating circuits of a testing arrangement embodying the present invention. Fig. 50 6 shows portions of an operator's sender and key set circuits.

The operator's key set as shown in Fig. 6 is not of the type commonly used, since in 55 operation as ordinarily practised, the number of impulses to be sent during the first two selections are determined by the depression of a single key, and the number of impulses sent during the remaining five selections are determined by the depression of 60 four keys in accordance with the numerical designation of the wanted line. Since, however, the keys associated with the testing arrangement are arranged to be depressed in accordance with the number of impulses 65 actually sent, it has been assumed that, in

this case, the operator will also depress keys in accordance with the number of impulses actually to be sent.

The regular operation of the sender to be tested, as used in setting up a connection between two subscribers, will first be described, after which its operation in connection with the testing device will be described.

If now we assume that the number of the wanted subscriber is 3416, and that his substation is served through an office whose trunks terminate in the third sub-group of the fifth main group of terminals served by the switch shown in Fig. 1, the operation will be as follows:

The operator will depress district brush key 2 and district group key 4. Since the number of the wanted line is 3416, a final switch must be seized which terminates in the second main group and second sub-group of the contacts of an incoming switch at the office selected, and, therefore, incoming brush key 1 and incoming group key 1 will have to be depressed. At the final switch the terminals of the wanted line will be found in a group served by the fourth brush, and therefore final brush key 3 will have to be depressed. Since the desired hundreds group has now been located, the depression of the No. 1 key in the tens column and the No. 6 key in the units column will serve to control the last two selections in obtaining the desired line.

The subscriber at substation 1, when desiring a connection, removes his receiver 100 from the hook, whereupon line relay 2 is energized to cause the display of a line signal 3 in the well-known manner. An operator, one of whose cords is indicated at O, upon observing the lighting of signal 3 inserts a plug 4 into a jack 5 associated with signal 3. A circuit is then completed from grounded battery, cut-off relay 6, sleeve contacts of jack 5 and plug 4, cord relay 7 to ground. Relays 6 and 7 are energized in this circuit, cut-off relay 6 operating to remove the control of line relay 2 from the calling subscriber, and relay 7 completing a circuit from grounded battery, power magnet of sequence switch 100, contact 102, front contact and armature of relay 7, to ground, for moving sequence switch 100 out of position 1 and into position 2, under the control of its normal spring 101. By depressing a listening key 8, the operator completes a talking circuit to the calling subscriber and may ask the number of the wanted line. Upon learning that the desired subscriber's number is 3416 in an office, the trunks to which terminate in the third sub-group of the fifth main group of trunks of the district selector, she will depress keys in the key set shown in Fig. 3 as previously described.

When the sequence switch 100 arrives in position 2, a circuit is completed from

ground, contact 103, contacts 202, 203, winding of relay 9, to grounded battery.

- Relay 9 is energized and at its right-hand armature and front contact completes a circuit from grounded battery, power magnet of sequence switch 200, contact 204, armature and front contact of relay 9 to ground, which moves sequence switch 200 from position 1 to position 2 under the control of its 5 normal spring 201. In position 2 of sequence switch 200, a circuit is completed from grounded battery, up-drive magnet 10, contact 205, armature and front contact of relay 9 to ground, which causes the cord 10 finder brush shaft 11 to be moved upwardly, advancing brushes 12, 13, 14, 15 and 16 over terminals 17, 18, 19, 20 and 21 associated with the various cord circuits. Relay 9, upon energization, locks itself over a path 15 from grounded battery, winding of relay 9, its left-hand armature and front contact, contacts 206 and 220, armature and back contact of test relay 22, to ground. When the cord finder brushes engage the terminals 20 of the proper cord, relay 22 is energized over a circuit from grounded battery, winding of relay 22, contact 207, brush 12, terminal 17, contact 104, to ground, and immediately locks up over a path from grounded battery, 25 winding of relay 22, contact 208, right-hand armature and front contact of relay 22, brush 13, terminal 18, contact 105, to ground. The energization of relay 22 opens one branch of the locking circuit of relay 9, 30 but this relay is maintained energized over a branch path from grounded battery, winding of relay 9, left-hand armature and front contact of relay 9, centering commutator 23, brush 24, to ground, until brush 24 engages an insulating segment of commutator 35 40 23, at which time the brush will be accurately centered on the terminals of the desired cord. Relay 9 then deenergizes, opening at its right-hand armature and 45 front contact the circuit of up-drive magnet 10 and completing at its right-hand armature and back contact a circuit from grounded battery, power magnet of sequence switch 200, contact 209, right armature and back contact of relay 9 to ground, which moves this sequence switch from position 50 2 to position 3.

- In position 3 of sequence switch 200, a circuit is completed from grounded battery, 55 power magnet of sequence switch 300, contact 302, contact 210, to ground, for moving sequence switch 300 out of position 1 and into position 3, under the control of its normal spring 301.
- 60 The operator having learned the number of the wanted line and having depressed the proper keys, now depresses a start key 25, which completes a circuit from grounded battery, power magnet of sequence switch 65 300, contact 303, contacts of key 25, to

ground, which moves this sequence switch from position 3 to position 4.

A circuit is now completed for the district line relay 26 over the fundamental circuit, from grounded battery, winding of relay 26, contact 106, conductor 27, terminal 20, finder brush 15, outer armature and back contact of the upper O' counting relay, windings of stepping relay 28, contact 304, finder brush 14, terminal 19, conductor 29, 70 contact 107, to ground. Relay 26 locks itself to conductor 27 through its left-hand armature and front contact and contact 108, and also completes a circuit from grounded battery, power magnet of sequence switch 100, 75 conductor 30, contact 109, right-hand armature and front contact of relay 26 to ground, for moving sequence switch 100 out of position 2 and into position 3.

In position 3 of sequence switch 100, a 80 circuit is completed from grounded battery, power magnet 31, contact 110, right-hand armature and front contact of relay 26, to ground. Brush rod 32 is moved upward under the control of power magnet 31 and 85 advances the brush sets carried by it to a position wherein one of them may be tripped.

Upon the first closure of the fundamental circuit, stepping relay 28 was energized, 90 whereupon a circuit was completed for the No. 4 counting relay, from grounded battery, winding of No. 4 counting relay, armature and back contact of No. 4' counting relay, contacts of depressed key 4 in the 100 district brush column, contact 305, armature and front contact of stepping relay 28, to ground. Relay 4 is energized and prepares a path for the No. 4' counting relay in the well-known manner.

105 As the brush rod 32 moves upward, the circuit of stepping relay 28 is intermittently shunted by a branch of the locking circuit of relay 26, which extends through contacts 108 and 111, conductor 33, commutator 34, 110 brush 35, to ground. The action of relay 28 results in the successive actuation of the counting relays in the well-known manner. When the upper O' counting relay is energized, the branch of the fundamental circuit through stepping relay 28 is permanently broken, and when, an instant later, centering brush 35 engages an insulating segment of commutator 34, relay 26 is deenergized, opening at its right-hand armature 115 the circuit of up-drive magnet 31 and maintaining brush rod 32 in a position wherein the fifth set of brushes may be tripped. A circuit is also completed from grounded battery, power magnet of sequence switch 120 100, conductor 30, contact 112, armature and back contact of relay 26 to ground, for moving this sequence switch from position 3 to position 4. A circuit is now completed from grounded battery, winding of trip magnet 125 130

49, contact 118 to ground, to operate the trip rod to release the positioned set of brushes.

The energization of the upper O' counting relay completes a circuit from grounded 5 battery, power magnet of sequence switch 300, inner armature and front contact of the upper O' counting relay, contact 306 to ground, which moves this sequence switch from position 4 to position 6.

10 When sequence switch 300 leaves position 4, the locking circuit of the counting relays is broken at contact 307 and they are deenergized.

In position 4 of sequence switch 100, and 15 in position 6 of sequence switch 300, relay 26 is again energized over the fundamental circuit previously described, and again locks itself to conductor 27. A circuit is also completed from grounded battery, power 20 magnet of sequence switch 100, conductor 30, contact 109, armature and front contact of relay 26 to ground, for moving this sequence switch out of position 4 and into position 5.

25 In position 5 of sequence switch 100, the circuit of up-drive magnet 31 is again closed from grounded battery, winding of magnet 31, contact 110, armature and front contact of relay 26 to ground, again causing upward 30 motion of the brush rod 32.

The closure of the fundamental circuit again causes the energization of stepping relay 28. A circuit is then completed from 35 grounded battery, winding of the No. 2 counting relay, contacts of key No. 2 in the district group column, contact 308, armature and front contact of stepping relay 28, to ground. Counting relay No. 2 is energized and prepares a circuit for the No. 2' 40 counting relay in the well-known manner.

45 During the upward motion of the brush rod, stepping relay 28 is again intermittently shunted by a branch of the locking circuit of relay 26, through contacts 108, 113, conductor 36, accurate centering segment 37, brush 38, to ground. The action of stepping relay 28 results in the successive energization 50 of the counting relays. When the O' counting relay is energized, it opens at its outer armature the lower branch of the locking circuit of relay 26. When brush 38 engages an insulating portion of commutator 37, relay 26 is deenergized, opening 55 at its right-hand armature the circuit of the up-drive magnet 31, and stopping the brush shaft with the fifth set of brushes at the bottom of the third sub-group of trunks, the trunks therein leading to the desired office. The O' counting relay at its inner 60 armature and front contact completes a circuit for moving sequence switch 300 from position 4 to position 6. Relay 26, upon deenergization, also completed a circuit from 65 grounded battery, power magnet of sequence switch 100, conductor 30, contact 112, right-

hand armature and back contact of relay 26, to ground, for moving this sequence switch out of position 5 and into position 11.

It is to be understood that the brush rod 70 32 is again advanced to hunt for an idle trunk in the selected group, in some sequence switch position between 5 and 11, and upon the seizure of such trunk, is advanced to position 11, but it has not been considered necessary to disclose this well-known operation. 75

The incoming switch, indicated by brushes and terminals at 39, is operated in accordance with the setting of the keys in the incoming brush and incoming group columns 80 in positions 8 and 10 of the sending sequence switch 300. Hunting then takes place at the incoming switch, and when an idle final switch has been seized, it is set in accordance with the designation of the final brush, tens 85 and units keys, in positions 12, 14 and 16 of the sender sequence switch. The final switch is indicated by brushes and terminals at 40 in Fig. 1. When the sender sequence switch is moved out of position 16 upon the final 90 energization of the O' counting relay, the sender sequence switch moves from position 16 to position 1. In passing through positions 17 and 18, a circuit is completed from grounded battery, power magnet of sequence 95 switch 200, contact 309 to ground, which moves sequence switch 200 from position 4 to position 8.

In position 8 of sequence switch 200, a 100 circuit is completed from ground, contact 211, brush 16, terminal 21, conductor 41, contact 114, power magnet of sequence switch 100, to grounded battery, which moves sequence switch 100 from position 11 to position 16. 105

110 After the sender sequence switch 300 has returned to normal position, a circuit is completed from grounded battery, down-drive magnet 42, contact 310, contact 212, to ground. Brush rod 11 is returned to normal position under the control of magnet 42, and when it reaches normal position, a circuit is completed from grounded battery, power magnet of sequence switch 200, contact 213, commutator segment 43, brush 44, to ground, 115 which moves sequence switch 200 from position 8 to position 1, and breaks the circuit of down-drive magnet 42.

120 Sequence switch 100 is now in position 16, which is the talking position, and it has been assumed that the switches 39 and 40 have moved into their talking positions after the called subscriber has been successfully signaled. The connection is now complete and the parties may converse. 125

130 At the conclusion of conversation, both parties replace their receivers and the operator at O is informed by the lighting of supervisory signals (not shown), controlled by supervisory relays 45 and 46, that con-

nection is no longer desired. She thereupon removes plug 4 from jack 5, causing the deenergization of relay 7, which completes a circuit from grounded battery, power magnet of sequence switch 100, contact 115, armature and back contact of relay 7, to ground, for moving this sequence switch from position 16 to position 18. A circuit is now completed from grounded battery, 10 down-drive magnet 47, contact 116, to ground.

The brush rod 32 is restored to its normal position, and on reaching normal position a circuit is closed from grounded battery, 15 power magnet of sequence switch 100, conductor 30, contact 117, commutator segment 48, brush 38 to ground, which moves this sequence switch from position 18 into position 1, thereby opening the circuit of magnet 47. The restoration of a district switch causes the restoration of switches 39 and 40 in the well-known manner. All parts of the apparatus have now been restored to their normal positions and are ready for re-use.

25 If it is desired to test the accuracy of operation of the sender, this may be done by connecting jacks 54 and 55 with jacks 50 and 51 by means of link connectors 52 and 53. Assuming that the same number of 30 pulses are to be sent as in the previous setting of the connecting switches, the same keys will be set in the operator's key set shown in Fig. 6, that is, key No. 4 in the district brush column, key No. 2 in the district group column, key No. 1 in the incoming brush column, key No. 1 in the incoming group column, key No. 3 in the final brush column, key No. 1 in the tens column and key No. 6 in the units column. Corresponding keys will be depressed on the test 35 box key set shown in Fig. 5.

The testing operator now depresses start key 56, whereupon a circuit is completed from grounded battery, power magnet of 45 progress-controlling sequence switch 400, contact 402, contacts of start key 56, to ground, which causes sequence switch 400 to move out of position 1 and into position 2 under the control of its normal spring 401. 50 A circuit is now completed from grounded battery, winding of relay 9, contacts 203, 202, jack 55, sleeve conductor of link 53, sleeve contact of jack 51, contact 403, to ground. Relay 9 is energized and completes a circuit from grounded battery, power magnet of sequence switch 200, contact 204, right armature and front contact of relay 9 to ground, which moves the sequence switch out of position 1 and into 55 position 2. Relay 9 locks up over a circuit from grounded battery, winding of relay 9, its left-hand armature and front contact, contacts 206 and 220, left-hand armature and back contact of relay 22, to ground.

60 In position 2 of sequence switch 200, a

circuit is completed from grounded battery, up-drive magnet 10, contact 205, right-hand armature and front contact of relay 9 to ground, which causes the cord finder brush shaft 11 to be moved upwardly, advancing 70 the brushes 12, 13, 14, 15 and 16 over terminals 17, 18, 19, 20 and 21 respectively. When the cord finder brushes engage the terminals to which the test jacks 54 and 55 are connected, relay 22 is energized over a circuit 75 from grounded battery, winding of relay 22, contact 207, brush 12, terminal 17, ring contact of jack 55, ring conductor of link 53, ring contact of jack 51, contact 404, to ground, and immediately locks up over a 80 path from grounded battery, winding of relay 22, contact 208, right-hand armature and front contact of relay 22, brush 13, terminal 18, tip contact of jack 55, tip conductor of link 53, tip contact of jack 51, contact 405 85 to ground. The energization of relay 22 opens one branch of the locking circuit of relay 9, but this relay is maintained energized over a branch path as previously described until the brush set is accurately centered on the desired terminal set. Relay 9 then deenergizes, opening at its right-hand armature and front contact the circuit of up-drive magnet 10, and completing at its right-hand armature and back contact a circuit 90 to move sequence switch 200 from position 2 to position 3 as previously described.

From this point the operation is the same as previously described until sequence switch 300 arrives in position 4, at which time sequence switch 200 is also in position 4. Relay 57 is now energized over the fundamental circuit extending from grounded battery, left-hand armature and back contact of relay 58, conductor 59, contact 406, tip contact of jack 50, tip conductor of link 52, tip contact of jack 54, terminal 20, brush 15, outer armature and back contact of the O' counting relay, winding of stepping relay 28, contact 304, brush 14, terminal 19, ring 100 contact of jack 54, ring conductor of link 52, ring contact of jack 50, contact 407, to ground. 105

Relays 57 and 28 are energized in this circuit, relay 57 locking itself to conductor 59 115 through its left-hand armature and front contact, while stepping relay 28 completes a circuit for the No. 4 counting relay through the closed contacts of key No. 4 in the district brush column, as previously described.

The impulse sequence switch 500 may be a sequence switch of the usual type of construction and is arranged to continue rotation after being started as long as relay 57 is 120 energized, and operates to shunt out the stepping relay circuit by the intermittent closure of its contact 504, as will presently be described. This sequence switch does not return to normal position, but is advanced a 125 130

desired number of steps from the position in which it was last brought to rest. It will be assumed that sequence switch 500 is resting in position 5 at the beginning of the 5 present operation.

- When sequence switch 400 arrives in position 2 with sequence switch 500 in position 5, a circuit will be completed from ground, contact 408, right-hand armature and back contact 409, conductor 400, left-hand winding of relay 58, contact 501, left-hand armature and back contact of relay 60 to grounded battery. Relay 60 is energized and locks up over a path from grounded battery, inner armature and back contact of relay 61, contact 409, conductor 62, right-hand winding of relay 60, right-hand armature and front contact of relay 60 to ground.

- Relays 60 and 57 being energized, a circuit is completed from grounded battery, 20 left-hand armature and back contact of relay 63, contact 502, left-hand armature and back contact of relay 64, contact 503, left-hand armature and back contact of relay 65, contact 505, left-hand armature and back contact of relay 66, contact 506, left-hand armature and back contact of relay 67, contact 507, left-hand armature and front contact of relay 68, contact 508, left-hand winding of relay 58, left-hand armature and back contact of relay 68, right-hand armature and front contact of relay 57 to ground. Relay 58 is energized in this circuit and completes a locking circuit for itself from grounded battery, outer armature and back contact of relay 61, winding of relay 68, right-hand winding of relay 58, right-hand armature and front contact of relay 58, contact 408, to ground.

- Relay 68 is energized in this circuit and 40 completes a circuit from grounded battery, power magnet of sequence switch 500, left-hand armature and front contact of relay 68, right-hand armature and front contact of relay 57 to ground, which causes the impulse 45 sequence switch 500 to be moved out of position 5 and into a position determined by the operation of the sender shown in Fig. 6.

- When sequence switch 500 reaches position 5 $\frac{1}{2}$, stepping relay 28 is deenergized to permit the energization of the No. 4' counting relay, since stepping relay 28 is shunted by a path from grounded battery, winding of relay 57, left-hand armature and front contact of relay 57, contact 504, to ground. 55 When sequence switch 500 leaves position 5 $\frac{1}{2}$, the stepping relay is again energized and in turn energizes the No. 3 counting relay. In position 6 $\frac{1}{2}$ of sequence switch 500, stepping relay 28 is again shunted and allows the No. 60 3' counting relay to energize. When sequence switch 500 leaves position 6 $\frac{1}{2}$, the No. 2 counting relay is energized, this process continuing until the O' counting relay is energized, which will take place when sequence switch 500 arrives in position 9 $\frac{1}{2}$.

The energization of the O' counting relay results in the permanent opening of the lower branch path of relay 57, and when sequence switch 500 leaves position 9 $\frac{1}{2}$, the upper branch path of relay 57 is broken, 70 whereupon it deenergizes and sequence switch 500 will move into position 10 under the control of its normal spring 509 and stop in this position.

With sequence switch 400 in position 2, 75 lamp 69 is lighted over a circuit from grounded battery, lamp 69, contact 410 to ground, indicating to the operator that the progress-controlling sequence switch 400 is in position 2, in which position the district 80 brush selecting impulses are to be sent. At the same time a circuit exists for matching lamp 70 from grounded battery, lamp 70, closed contacts of district brush key No. 4, conductor 71, contact 410 to ground. The 85 lighting of these two lamps informs the testing operator that the district brush selecting impulses are being sent at this stage of operation and that the No. 4 key has been depressed.

In position 10 of sequence switch 500, with relay 60 energized and with relays 63, 64, 65, 66 and 67 deenergized, relay 57 also being deenergized, a circuit is completed from grounded battery, conductor 72, lamp 73, 95 inner left-hand armature and back contact of relay 74, outer left-hand armature and back contact of relay 75, conductor 76, contact 510, conductor 77, outer right-hand armature and front contact of relay 60, outer 100 armatures and back contacts of relays 67, 66 and 65 respectively, outer right-hand armature and front contact of relay 68, right-hand armature and back contact of relay 57 to ground. The lighting of lamp 73 adjacent 105 to lamp 70 informs the testing operator that the desired number of impulses have been correctly sent.

A circuit is also completed at this time for relay 78, from grounded battery, winding 110 of relay 78, contact 411, conductor 79, closed contacts of key No. 4 in the district brush column, conductor 80, to ground at the right-hand armature and back contact of relay 57 over the path just traced for lighting lamp 73. 115

During the sending of impulses, relay 81, which has two windings in differential relation to one another, is not energized, since circuits are completed through both its windings, the circuit through its right-hand winding extending from grounded battery, right-hand armature and back contact of relay 81, the right-hand winding of relay 81, contacts 412 and 413, to ground; the circuit through its left-hand winding extending 120 from grounded battery, left-hand winding of relay 81, conductor 82, to ground at the inner right-hand armature and front contact of relay 68. The energization of relay 78 therefore completes a circuit from 125 130

grounded battery, power magnet of sequence switch 400, left-hand armature and back contact of relay 81, armature and front contact of relay 78 to ground, for moving sequence switch 400 out of position 2 and into position 3.

The presence of relay 81 prevents sequence switch 400 from passing through more than one position at a time, which 10 might occur if relay 68 was slow to release, and a set of impulses, equal in number to the set previously sent, is again to be sent in the position to which sequence switch 400 has just moved. In this event the energizing 15 circuit for relay 78 would again be completed, since the sequence switch 500 would be set in a position corresponding to that assumed upon the completion of the sending of the desired set of impulses, and sequence switch 500 would therefore not be allowed 20 time to operate.

When sequence switch 400 leaves position 2, the circuit through the right-hand winding of relay 81 is broken at contacts 412 25 and 413, and relay 81 energizes over a circuit from grounded battery, left-hand winding of relay 81, conductor 82, to ground at the inner right-hand armature and front contact of relay 68. The energized condition 30 of relay 81 will prevent sequence switch 400 from moving out of position 3 in case the above described condition should take place. The energization of relay 81 also completes a circuit from grounded battery, right-hand 35 armature and front contact of relay 81, winding of relay 61 to ground, which attracts its armatures and opens the locking circuit of relay 60 at its inner armature, and at its outer armature introduces a second 40 break in the circuit of relays 68 and 58, which circuit was previously broken at contact 408 when sequence switch 400 left position 2. This second break in the circuit of relay 68 insures against the possibility of 45 relay 68 being again energized when sequence switch 400 arrives in position 3.

The energization of the O' counting relay completed a circuit from grounded battery, power magnet of sequence switch 300, 50 inner armature and front contact of the O' counting relay, contact 306 to ground, which moves sequence switch 300 from position 4 to position 6.

With sequence switch 400 in position 3, a 55 circuit is completed for progress lamp 83, from grounded battery, lamp 83, contact 414, to ground, and a circuit is completed for matching lamp 84 from grounded battery, lamp 84, closed contacts of district 60 group key No. 2, conductor 85, contact 414 to ground. The lighting of progress lamp 83 informs the testing operator that the district group impulses are to be next sent, and the lighting of lamp 84 shows which lamp

in the second series of matching lamps 65 should next be lighted.

With sequence switch 500 in position 10 and sender sequence switch 300 in position 6, relay 57 is again energized over the fundamental circuit. With sequence switch 400 in 70 position 3, a circuit is completed from grounded battery, left-hand winding of relay 67, contact 511, right-hand armature and back contact of relay 58, contact 408 to ground. At the same time a circuit is completed from grounded battery, left-hand winding of relay 64, contact 512, right-hand armature and back contact of relay 58, contact 408 to ground. Relays 64 and 67 lock 75 up through their right-hand windings to 80 conductor 62. The energization of relay 64 completes a circuit from grounded battery, outer right-hand armature and front contact of relay 64, conductor 86, windings of relays 87, 88, 74, 89 and 90 in parallel to 85 ground.

Relay 58 is energized over a circuit from grounded battery, left-hand armature and back contact of relay 63, contact 502, left-hand armature and front contact of relay 64, contact 513, left-hand armature and back contact of relay 65, contact 505, left-hand armature and back contact of relay 66, contact 506, left-hand armature and front contact of relay 67, contact 514, left-hand armature and back contact of relay 60, contact 515, left-hand winding of relay 58, left-hand armature and back contact of relay 68, right-hand armature and front contact of relay 57 to ground. Relay 58 is energized 100 and locks up through its right-hand winding in series with relay 68, as previously described. The energization of relay 68 at its left-hand armature and front contact, completes a circuit for moving sequence 105 switch 500 out of position 10 and into a position determined by the operation of the sender shown in Fig. 3.

It is to be observed that the circuits extending through the left-hand armatures of 110 relays 60, 63, 64, 65, 66 and 67 and certain sequence switch contacts associated with them, serve as a check upon the operation of the relays, since if the proper relays have not been operated in accordance with the 115 position from which sequence switch 500 is starting, the progress of the test will be stopped, since relay 58 cannot be energized.

As before, the circuit of stepping relay 28 is intermittently shunted by the action 120 of contact 504, and when the O' counting relay is energized, which occurs when sequence switch 500 leaves position 12 $\frac{1}{2}$, relay 57 is deenergized and sequence switch 500 will come to rest in position 13. At this 125 time a circuit is completed for lamp 91 from grounded battery, conductor 72, lamp 91, inner right-hand armature of relay 89,

- outer right-hand armature and back contact of relay 92, conductor 93, contact 516, conductor 94, outer right-hand armature and front contact of relay 67, outer right-hand armatures and back contacts of relays 66 and 65, outer right-hand armature and front contact of relay 68, right-hand armature and back contact of relay 57, to ground. The lighting of lamps 84 and 91 again indicates to the testing operator that the correct number of impulses have been sent. Relay 78 is energized as before and sequence switch 400 is advanced from position 3 to position 4.
- 15 The testing operation continues in a manner similar to that described until all the sets of impulses have been sent, the last set of impulses being sent in position 8 of sequence switch 400. When sequence switch 400 is moved out of position 8, it returns to its first or normal position under the control of its normal contact 401, and the testing apparatus is in condition for re-use.
- 20 25 What is claimed is:
1. In an indicating system, a plurality of signals, a multi-position counting device, means to move said counting device, means to display a desired signal in accordance with the extent of movement of said counting device, regardless of the position of said counting device at the beginning of its movement.
  2. In an indicating system, a plurality of indicating signals, a multi-position counting device, means to advance said counting device through a desired number of positions, and means to display a signal indicative of the number of positions through which said counting device was moved, regardless of which position said counting device was in when started.
  3. In an indicating system, a plurality of signals, a multi-position counting device, contacts controlled thereby, a combination of locking relays, means to energize certain ones of said relays in accordance with the position of said counting device before its operation, means to advance said counting device through a desired number of positions, and circuits controlled jointly at contacts of said relays and at contacts controlled by said counting device to cause the display of a signal indicative of the number of positions through which said counting device is moved, regardless of which position said counting device was in when started.
  4. In an indicating system, a plurality of signals, a multi-position counting device, a combination of locking relays, means to energize certain ones of said relays in accordance with the position of said counting device before its operation, a starting circuit for said counting device controlled at

contacts of said locking relays, and means to complete said starting circuit only when desired ones of said relays have been energized.

5. In an indicating system, a plurality of signals, a multi-position counting device, contacts controlled thereby, a combination of locking relays, means to energize certain ones of said relays in accordance with the position of said counting device before its operation, a starting circuit for said counting device controlled at contacts of said locking relays, means to complete said starting circuit only when desired ones of said relays have been energized, means to advance said counting device through a desired number of positions, and circuits controlled jointly at contacts of said relays and at contacts controlled by said counting device to cause the display of a signal indicative of the number of positions through which said counting device is moved, regardless of the position of said counting device at the beginning of its movement.

6. In a switch-controlling system, a multi-position switch, an operating circuit therefor, a differentially wound relay, said operating circuit being controlled at a back contact of said relay, automatic apparatus to be used in conjunction with said multi-position switch, a circuit through one winding of said differentially wound relay controlled at contacts of said multi-position switch, a circuit through the other winding of said differentially wound relay controlled by said associated apparatus, and means to energize one winding only of said relay to prevent movement of said switch at times when said switch and said associated apparatus are not in corresponding stages of operation.

7. In a testing system, a sending device arranged to send a plurality of sets of impulses, a counting device, a control switch therefor, means to position said counting device in response to a set of impulses, means operated in accordance with the extent of movement of said counting device to indicate whether or not the successive sets of impulses have been correctly sent, regardless of the position of said counting device at the beginning of its movement, and means to advance said control switch to a position wherein said counting device may be operated in response to the next set of impulses.

8. In a testing system, a sending device arranged to transmit a plurality of sets of impulses, a control switch therefor, means to successively operate said sending device, a testing operator's key set, a testing device including a counting device and a controlling switch therefor, a series of lamps, means to light a desired one of said lamps in accordance with the setting of said key set, a

second series of lamps, means to position said counting device in accordance with the operation of said sender, means to light a lamp in said second series of lamps in accordance with the extent of movement of said counting device, regardless of the position of said counting device at the beginning of its movement, said two series of

lamps being placed in such relation that adjacent lamps will be lighted when a set 10 of impulses is correctly sent.

In witness whereof, I hereunto subscribe my name this 28th day of December, A. D., 1916.

WILLIAM H. MATTHIES.
